DESIGN FOR A DOLL OR SIMILAR ARTICLE

Le Ray Fowler, New York, N. Y.

Application April 7, 1938, Serial No. 76,355

Term of patent 3½ years

To all whom it may concern:

Be it known that I, Le Ray Fowler, a citizen of the United States and a resident of the Borough of Manhattan, in the county, city, and State of New York, have invented a new, original, and ornamental Design for a Doll or Similar Article, of which the following is a specification, reference being had to the accompanying drawing forming a part thereof.

Fig. 1 is a front elevational view of a doll showing my new design.

Fig. 2 is a side elevational view thereof.

I claim:

The ornamental design for a doll or similar article, substantially as shown.

L. RAY FOWLER.
